(57) **CLAIM**

The ornamental design for an insect trap, as shown and described.

DESCRIPTION

FIG. 1 is a perspective view of an insect trap showing our new design;

FIG. 2 is a front elevational view thereof;

FIG. 3 is a left side view thereof, the right side view is a mirror image of FIG. 3;

FIG. 4 is a top view thereof;

FIG. 5 is a bottom view thereof;

FIG. 6 is a perspective view thereof with the items showing setting removed; and,

FIG. 7 is an upper perspective view of an alternative embodiment of an insect trap showing our new design providing an alternative embodiment incorporating the same design.

Items shown in broken line or chain line form no part of the inventive design and are shown for the purpose of setting or application only. The back of the trap is without ornamentation.
